UNITED STATES PATENT OFFICE.

JAMES SIMPSON AND HARRY E. CLAY, OF MCKEESPORT, PENNSYLVANIA.

APPARATUS FOR HANDLING AND FORMING PIPE-SKELP.

1,391,912.

Specification of Letters Patent. Patented Sept. 27, 1921.

Application filed November 18, 1920. Serial No, 423,924.

To all whom it may concern:

Be it known that we, JAMES SIMPSON and HARRY E. CLAY, both citizens of the United States, and residents of McKeesport, in the 5 county of Allegheny and State of Pennsylvania, have invented certain new and useful Improvements in Apparatus for Handling and Forming Pipe-Skelp, of which the following is a specification.

10 The invention relates to apparatus for handling and forming pipe skelp, and relates particularly to a novel combination of cutting-off shears, transfer tables, and clipping and cupping shears, adapted to automatically 15 convey the skelp from the cutting-off shears and onto the clipping table, and automatically clipping and cupping the end of said skelp.

One object of the invention is to provide 20 automatic control means for controlling the operation of the transfer tables so as to prevent piling or jamming of the skelp.

Another object of the invention is to provide 25 automatic centering means for centering and placing the skelp in position for clipping and cupping.

Heretofore, in making skelp the blanks were rolled to the proper thickness and then 30 cut the proper lengths at the cutting-off shears and piled. The piles were then moved by a crane or otherwise to a cooling bed where they remained until cooled. After being cooled the piles were again 35 moved by a crane onto suitable trucks or buggies which hauled them to the cupping and clipping shears and table where the skelp was cupped and clipped by hand.

This old method was slow and required 40 the use of a number of skilled men which made the operation costly. By the above method it required several clipping and cupping shears to clip and cup the output from one mill.

By the use of the present apparatus, all 45 handling of the skelp manually from the time it is sheared or cut to length at the cutting-off shear until it is clipped and cupped, is eliminated, the clipping and cupping operation being entirely automatic, and two 50 sets of apparatus are able to handle the complete maximum output of the mill.

One form of apparatus embodying our invention will be described in detail in the following specification, and illustrated in the 55 accompanying drawings, in which—

Figure 1 is a top plan of our improved apparatus.

Fig. 2 an enlarged fragmentary plan showing the cutting-off shear.

Fig. 3 is a sectional elevation, taken on 60 the line III—III of Fig. 2.

Fig. 4 is a sectional elevation, taken on 65 the line IV—IV of Fig. 3, showing the operating and control mechanism for the transfer table.

Fig. 5 is an enlarged elevation of the 70 cutting-off shear, showing details of the ratchet and seal for operating and controlling the conveying mechanism of the transfer table.

Fig. 6 is a similar view showing the ratchet advanced one-half revolution.

Fig. 7 is a side elevation of the cutting-off shear, and ratchet and seal mechanism.

Figs. 8 and 9 are sectional side elevations, 75 showing details of the seal operating mechanism.

Fig. 10 is a cross-sectional elevation on the line X—X of Fig. 9, showing the seal in 80 operative position on the ratchet.

Fig. 11 is a fragmentary plan showing the clipping and cupping shears.

Fig. 12 is a side elevation of the clipping and cupping shears.

Fig. 13 is a front elevation of the clipping and cupping shears.

Fig. 14 is a rear elevation of the clipping and cupping shears, showing fragmentary portions of the associated mechanism.

Fig. 15 is an enlarged fragmentary side 90 elevation of the jaw portion of the clipping and cupping shears.

Fig. 16 is a top plan of a piece of skelp that has passed the clipping and cupping shears.

Fig. 17 is a side elevation of the piece of skelp shown in Fig. 16.

Fig. 18 is a front end elevation of the skelp shown in Figs. 16 and 17.

Referring to the drawings, the letter A 100 designates the cutting-off shear which shears the skelp to proper length as it is delivered to the transfer table B. The transfer table B is connected to and overlaps the clipping table C which conveys the skelp to and away 105 from the clipping and cupping shears D.

The cutting-off shears A are of well known construction, and comprise a bed-plate 2, a housing 3, drive shaft 4, gears 5, operating shaft 6, shear blade 7, and shear block 8.

The transfer table B is located in the front of the shears and comprises a plurality of supporting members 9 supporting a

top portion formed of suitable skids or rails 10 spaced apart. A drive shaft 11 is journaled along the forward edge of the table and carries a plurality of sprocket wheels 12 spaced apart so as to be in alinement with spaces between the rails 10. A plurality of idler sprocket wheels 13 are journaled in suitable brackets 14 along the rear edge of the table in alinement with the sprocket wheels 12 on the shaft 11. Suitable conveyer chains 15 are trained about the sprocket wheels 12 and 13 and carry a plurality of spaced dogs 16 adapted to engage the skelp at the shear and move it forward as the chains rotate.

The chains 15 are rotated by the sprockets 12 on the shaft 11, which receives its power from the shaft 17 through beveled gears 18 and 19.

20 The shaft 17 receives its power from the sheer A and is adapted to be intermittently driven by means of a disk 20 secured on the end of the shaft 21 journaled in the upper forward end of the shear housing 3, and 25 which is geared to the operating shaft 6 of the shear by gears 22 and 23 having a ratio of two to one, so that one revolution of the shaft 6, which causes one operation of the shears will also rotate the shaft 21 and the 30 disk 20 only one-half revolution. Left-hand and right-hand connecting rods 24 and 25, respectively, are pivotally mounted in the disk 20, and have their lower ends pivotally secured to driving arms 27 and 28, respectively, which are journaled on shoulders formed on the ratchet wheel 30, and carry pivoted dogs 29. The dogs 29 of the arms 27 and 28 are each adapted to engage in the notches in a ratchet wheel 30 having notches 30^a, and secured on the shaft 17. As the shaft 21 and disk 20 are rotated, if the eccentric pin be in its uppermost position, the rods 24 and 25 will move downward, the right-hand connecting rod 25 forcing its 45 pawl or dog 29 against one of the notches 30^a of the ratchet wheel 30, thus moving the ratchet around a predetermined distance and rotating the shafts 17 and 11, and moving the conveyer chains 15 forward. While the 50 right-hand rod 25 and its pawl are forcing the ratchet 30 around, the left-hand rod 24 and its pawl or dog 29 are moving down freely along the other side of the ratchet ready to engage one of the other notches 30^a 55 on the next half revolution of the disk 20, which will move the rods 24 and 25 and pin 26 to their upper or starting position again. During the last half revolution of the disk and upward movement of the rods 24 and 25, the rod 25 will move its dog 29 freely up 60 along the ratchet 30 into position to engage one of the notches 30^a on the next operation of the shear. Each operation or complete stroke of the shear will cause the shaft 21 and disk 20 to revolve one-half revolution,

and at each half revolution the chains 15 will be moved a predetermined distance. The eccentric positioning of the pin 26 provides a dead center position at the beginning of each revolution, so that the operating shaft 6 of the shears may move a considerable amount or sufficient to shear the skelp before the pawls or dogs 29 move the ratchet any appreciable amount. However, after the pin 26 is past dead center, and while the shears are completing their stroke, the pin will be moving through a greater space and the rods 24 and 25 will be reciprocated considerably, thereby rotating the shafts 17 and 11 and chains 15 to convey the cut skelp away from the shears.

This operation will be repeated at each cutting stroke of the shears, and therefore the cut skelp will be moved automatically, step by step, along the transfer table B.

As the skelp is moved along the transfer table B it will engage a counterweighted rocking lever 32 pivotally mounted on a bracket secured beneath the table. The lever 32 is positioned at that portion of the table B that overlaps the clipping table C and is connected by a connecting rod 33 to a crank arm 33^a which is secured to a stub shaft 34 that is journaled under the table B, adjacent to its rear edge. The shaft 34 has a second crank 35 secured thereon which is connected by a connecting rod 35^a to one end of a bell crank lever 36 which is pivotally mounted on a bearing bracket 37 secured to the table B. The other end of the bell crank is pivotally connected to a disk member or seal 38 journaled on the shaft 17 and having lugs 39 thereon adapted to engage the dogs 29 as the seal is rotated, and hold said dogs out of the notches 30^a. As the skelp moves onto the lever 32 it will rock, pulling the connecting rod 33 and crank 33^a, rocking shaft 34 and crank 35, which in turn will move the connecting rod 35^a forward so as to rock the bell crank lever 36, rocking the lever 36 rotates the seal 38, causing its lugs 39 to move into position over the notches 30^a in the ratchet 30, which will prevent the dogs 29 of the rods 24 and 25 from engaging therein and, thereby, allow the chains 15 on the table B to remain stationary. The skelp is conveyed forwardly from the lever 32 by a plurality of trolleys E on the clipping table C and, therefore, it is essential that the chains 15 on the transfer table deliver only one pack or pile of skelp at a time, and since the chains will remain idle until the pile of skelp is removed from the lever or trigger 32, only one pile will be delivered at a time.

As has been said above, the transfer table B, and the clipping tables overlap or telescope. The conveying trolleys E of the clipping table are adapted to travel over onto the transfer table and pull the skelp piles 130

from their position on the trigger 32, onto the clipping table.

The clipping table C comprises a plurality of supporting members 41 adapted to support a top frame 42 having a plurality of trolley guides 43 secured thereon adapted to support and guide the trolleys E. The top of the table is composed of metal plates 44 spaced to form trolley passage-ways 45.

10 The trolleys E are formed of trolley bars 46 adapted to reciprocate in the guides 43 and having a series of pivoted dogs 47 at equally spaced intervals in the length thereof. The upper ends of the dogs 47 are arranged to tilt downwardly when the bars are moved rearwardly on the table to permit their passage under the skelp, and are held by pins 48 against tilting when moved in the opposite direction. The upper ends of the 15 dogs 47 are adapted to engage the edges of the skelp and, by a step by step movement, transfer the skelp along the table.

The clipping and cupping shear D is located at the end of the clipping and cupping table C, and is of well known construction, provided with a novel combination bottom knife and die 49, a reciprocating combination upper knife and die 50, and a novel bending plunger 51. The plunger 51 is provided 20 with guide rods 52 which pass through suitable apertures 53 in an extension 54 of the reciprocating shear head 55, which carries the upper knife and die 50. The guide rods 52 extend through suitable apertures 56 in a bracket 57, thereby yieldably holding the plunger in raised position. Suitable gags 59 of greater diameter than the apertures 53 are removably secured around the other guides and are adapted to be engaged by the 25 head 55 as it moves down to clip the skelp. As the head 55 engages the gags 59 it will move the plunger 51 downwardly until it engages the skelp, bending it transversely. The gags 59 are removable to permit the use 30 of different sizes to permit lengthening or shortening the stroke of the plunger 51.

The trolleys E are adapted to be reciprocated by cranks 60 secured to the shaft 61, which is mounted in suitable bearings under 35 the table. This shaft 61 is adapted to be rocked by a crank arm 62 which is secured on one end thereof and is connected by links 63 to a second crank arm 63^a on the shaft 64, which is journaled in the bearing bracket 65 on the shear D. The shaft 64 is rocked by a crank 66 secured thereto and connected by a link 67 to a pin 68, which is mounted eccentrically in the disk 69 on the power operating shaft 70 of the shear. As the shaft 40 70 rotates it will rotate the disk 69 and reciprocate the link 67, thereby rocking the shaft 64 and reciprocating the cranks 62 and 63^a and link 63, thereby rocking the main shaft 61 which in turn will reciprocate the 45 trolleys through the cranks 60.

The pin 68 is so positioned in the disk 69 that during the half revolution of the shaft 70 that provides the down stroke of the shear, this pin will be moving toward the rear, and thus causing the trolleys to move 50 freely toward the transfer table for a new pile of skelp, and that during the last half revolution causing the up stroke of the shear, the pin will move forwardly and move the trolley forwardly to bring a new pile of 55 skelp under the knives.

Extending along the one end of the clipping and cupping table C at an angle to the line of feed of the trolleys E, is an inclined guide 90 by which the skelp or piles of skelp 80 while being moved sidewise on said table to the cupping and clipping shear, are moved endwise by engaging therewith.

A stop member is arranged to stop or center the skelp under the shear D which comprises a lever 72 having an apertured head 73. The lever 72 is pivotally mounted on a stub shaft 74 in the bracket 75 which is secured to the lower portion of the shear. A sleeve member 76 is mounted for sliding 90 movement in the head 73 and is adapted to be slidably adjusted by means of the screw 77 and nut 78. A stop bar 79 is secured to the sleeve 76 and has an upturned end or stop 80.

The stop bar 79 is normally held in the path of travel of the skelp by its own weight, but is adapted to be moved out of the path of travel by a cam 81 on the shaft 61, this cam engaging with the lower end of 100 the lever 72 and thereby rocking the shaft 74 to lower the stop bar. The cam 81 is positioned on the shaft to engage and rock the lever 72 while the trolleys are making their forward stroke.

The stop bar 79 and sleeve 76 are made adjustable to permit adjustment to various sizes of skelp which it is desired to center.

A pusher bar mechanism is provided to engage and push the skelp against the stop 110 80 of the stop bar 79. This pusher bar mechanism comprises a cam operated, two-piece bell-crank lever 81^a journaled on a stub shaft 82 mounted in the bracket 65, and being operated by the peripheral cam face 83 115 of the disk 69.

The lower end of the lever 81^a is provided with an aperture 84, and a sliding bearing block 85 is mounted in the aperture, being adjustably held in position by an adjusting screw 86. A pusher bar 87 has its rear end pivotally secured to the bearing block 85, and its forward end is adapted to be slidably supported on the bending plunger 51 which is mounted on the front face 125 of the shear.

A suitable stop 88 is provided on the shear which is adapted to be engaged by a lug 89 on the cam lever 81^a to prevent it dropping below the disk 69.

95

105

110

120

125

130

The pusher bar 87 is mounted in the bearing 85 to permit it being adjusted to various widths of skelp.

The pusher bar mechanism is so adjusted and timed that it will engage and push the skelp forwardly against the raised stop bar 79 while the trolleys E are making their return stroke for another pile of skelp and just prior to the engagement of the skelp by the clipping and cupping shears.

The operation of the apparatus is as follows—

The skelp blanks are conveyed along a suitable table from the rolls to the cutting-off shear, where, if desired, they may be piled so as to run two or more through the cutting-off shear A at the same time.

The skelp blanks are engaged by suitable pinch rollers and run through the cutting-off shear A to a stop or gage, the upper blade of the shear being in its raised position. As the blank engages the stop, the shear is operated, cutting off a portion of the skelp of the proper length. The operation of the shear A will cause the disk 20 to rotate, operating the arms or rods 24 and 25 and causing the dogs 29 to rotate the ratchet 30 and shafts 11 and 17, thus moving the conveyer chains 15 and causing them to engage and convey the cut skelp from in front of the shear A. Each operation of the shear will cause this last cycle of operations to be repeated and convey the skelp, step by step, along the transfer table until the first pile strikes the lever 32 which will be forced down and cause the disk 38 to seal the ratchet 30, making it inoperative. The action of the lever 32 is conveyed to the disk 38 through a series of levers, connecting rods, and cranks, as has been described.

It will thus be seen that while the skelp remains on the lever or trigger 32, the conveyer chains will remain stationary since they receive their power from the shaft 17 which is rotated by the ratchet 30.

The skelp is removed from above the trigger or lever 32 by the dogs 47 on the trolley bars 46 of the clipping table C, and these bars 46 are adapted to be reciprocated by the cranks 60 on the shaft 61. The shaft 61 is rocked by a system of links and cranks actuated by the disk 69 on the clipping and cupping shear, as before described.

As the trolley bars 46 and dogs 47 forming the conveyer trolleys E, move the skelp along the table, one end of the skelp will engage the inclined guide 90 and be moved endwise, so that the sheared end or ends of the skelp are positioned lengthwise between the clipping knives of the shear D when the skelp or pile of skelp reaches a position lengthwise in alinement with the center of the cupping and clipping mechanism, in position for cupping and clipping the ends of the skelp.

The skelp or pile of skelp in passing into position under the clipping and cupping shears D passes onto the stop bar 79, and the pusher bar 87 will engage one longitudinal edge of the skelp or pile of skelp and force the other edge into engagement with the stop portion 80 of the stop bar 79, thus centering the skelp or pile of skelp under the shears D.

After the end of the skelp or pile of skelp has been clipped and cupped the stop bar 79 will be lowered and the trolleys E will move the skelp forwardly to the edge of the table where it falls into a suitable receptacle or cradle.

While we have shown and described specific constructions for the various elements of our improved apparatus, we do not wish to be limited beyond the express limitations defined in the appended claims, since various modifications in construction and combination of parts will readily suggest themselves to those skilled in the art.

We claim:

1. The combination with a cutting-off shear and a combined clipping and cupping shear, of a transfer table for conveying the skelp from said cutting-off shear, a clipping table arranged to receive the skelp from said transfer table, and means for operating said tables.

2. The combination with a cutting-off shear and a combined clipping and cupping shear, of a transfer table for conveying the skelp from said cutting-off shear, means connected with said cutting-off shear for automatically operating said transfer table, a clipping table arranged to receive the skelp from said clipping and cupping shears, and means connected with said clipping and cupping shears for automatically operating said clipping table.

3. The combination with a cutting-off shear and a combined clipping and cupping shear, of a transfer table for conveying the skelp from said cutting-off shear, means connected with said cutting-off shear for automatically operating said transfer table, a clipping table arranged to receive the skelp from said clipping and cupping shears, means connected with said clipping and cupping shears for automatically operating said clipping table, and means operable by the skelp on said transfer table for controlling the delivery of skelp to said clipping table.

4. The combination with a cutting-off shear and a combined clipping and cupping shear, of a transfer table for conveying the skelp from said cutting-off shear, means connected with said cutting-off shear for automatically operating said transfer table, a clipping table arranged to receive the skelp from said transfer table and convey the same to said clipping and cupping shear, means connected with said clipping and cupping

shear for automatically operating said clipping table, means for moving the skelp endwise on said clipping table during its travel thereon, and means for stopping and centering the skelp at said clipping and cupping shear.

5. The combination with a cutting-off shear and a combined clipping and cupping shear, of a transfer table for conveying the skelp from said cutting-off shear, means connected with said cutting-off shear for automatically operating said transfer table, a clipping table arranged to receive the skelp from said transfer table and convey the same to said clipping and cupping shear, means connected with said clipping and cupping shear for automatically operating said clipping table, means for moving the skelp endwise on said clipping table during its travel thereon, and means associated with said clipping and cupping shear and automatically operated thereby for stopping and centering the skelp before it is clipped and cupped.

25 6. The combination with a cutting-off shear and a combined clipping and cupping shear, of a transfer table, said table comprising a top composed of a plurality of spaced skids, and a plurality of endless chain conveyers mounted in the spaces between said skids, means operable by said shear for automatically operating said conveyers a predetermined distance at each stroke of said shear, and a clipping table arranged to receive the skelp from said transfer table and convey the same to said clipping and cupping shears, means operable by said clipping and cupping shear for operating said clipping table, and means for stopping and centering the skelp at said clipping and cupping shear before it is clipped and cupped.

7. The combination with a cutting-off shear and a combined clipping and cupping shear, of a transfer table for conveying the skelp from said cutting-off shear, and a clipping table arranged to receive the skelp from said transfer table and convey the same to said clipping and cupping shear, said last named table comprising a top portion composed of a plurality of spaced plates, conveyer members mounted in the spaces between said plates, and means operable by said clipping and cupping shear for operating said conveyers.

55 8. The combination with a cutting-off shear and a combined clipping and cupping shear, of a transfer table for conveying the skelp from said cutting-off shear, and a clipping table arranged to receive the skelp from said transfer table and convey same to said clipping and cupping shear, said last named table comprising a top portion composed of a plurality of spaced plates, con-

veyer members mounted in the spaces between said plates, means operable by said clipping and cupping shear for operating said conveyers, and means for moving the skelp endwise along said table while being conveyed sidewise by said conveyers.

9. The combination with a cutting-off shear and a combined clipping and cupping shear, of a transfer table for conveying the skelp from said cutting-off shear, and a clipping table arranged to receive the skelp from said transfer table and convey the same to said clipping and cupping shear, said last named table comprising a top portion composed of a plurality of spaced plates, conveyer members mounted in the spaces between the plates, and a rock shaft and a series of cranks, levers and links connected with said clipping and cupping shear for actuating said conveyers.

10. The combination with a cutting-off shear and a combined clipping and cupping shear, of a transfer table for conveying the skelp from said cutting-off shear, and a clipping table arranged to receive the skelp from said transfer table and convey the same to said clipping and cupping shear, said last named table comprising a top portion composed of a plurality of spaced plates, conveyer members mounted in the spaces between the plates, and a rock shaft and a series of cranks, levers and links connected with said clipping and cupping shear for actuating said conveyers, and means for moving the skelp endwise along said table while being conveyed sidewise by said conveyers.

11. The combination with a cutting-off shear and a combined clipping and cupping shear, of a transfer table for conveying the skelp from said cutting-off shear, and a clipping table arranged to receive the skelp from said transfer table and convey the same to said clipping and cupping shear, said last named table comprising a top portion composed of a plurality of spaced plates, conveyer members mounted in the spaces between the plates, and a rock shaft and a series of cranks, levers and links connected with said clipping and cupping shear for actuating said conveyers, and means for moving the skelp endwise along said table while being conveyed sidewise by said conveyers, and means associated with said clipping and cupping shear and automatically operated thereby for stopping and centering the skelp before it is clipped and cupped.

In witness whereof I have hereunto signed my name.

JAMES SIMPSON.

In witness whereof I have hereunto signed my name.

HARRY E. CLAY.
